CLAIM

The ornamental design for a urinary catheter, as shown and described.

DESCRIPTION

FIG. 1 is a perspective view of a urinary catheter, showing our new design;
FIG. 2 is a top plan view thereof;
FIG. 3 is a bottom plan view thereof shown in FIG. 2;
FIG. 4 is an end elevational view thereof;
FIG. 5 is an end elevational view thereof, opposite that shown in FIG. 4;
FIG. 6 is a side elevational view thereof; and
FIG. 7 is a side elevational view thereof, opposite that shown in FIG. 6.
